UNITED STATES PATENT OFFICE.

CHARLES H. GOLDMAN, OF SAN FRANCISCO, CALIFORNIA.

SAMPLE CARD.

Application filed May 22, 1922. Serial No. 562,817.

To all whom it may concern:

Be it known that I, CHARLES H. GOLDMAN, a citizen of the United States, residing in the city and county of San Francisco and State of California, have invented a new and useful Improvement in a Sample Card, of which the following is a specification.

My invention relates to improvements in sample folders for the display of materials and fashions of merchandise.

The primary object of my invention is to provide an improved folder for the reception and display of merchandise samples.

Another object of my invention is to provide an improved device arranged to display a sample of material in such manner as to simulate the appearance of an article fashioned therefrom.

A further object is to provide a folder arranged to receive a detachable fashion card having samples of materials connected therewith, whereby a single folder may be utilized with succeeding fashion cards and samples as the fashions and materials are changed through the several seasons of the year.

A still further object is to provide an improved folder which will present an attractive appearance at a nominal cost, and which is of a compact form suitable for mailing.

I accomplish these and other objects by means of the device disclosed in the drawings form a part of the present specification wherein like characters of reference are used to designate similar parts throughout said specification and drawings and in which:—

Fig. 1 is a broken front elevation of my improved folder opened to displaying position.

Fig. 2 is an end elevation of the device as shown in Fig. 1, the wings being slightly raised to show their connection upon the folder.

Fig. 3 is an end elevation of the device in folded position.

Referring to the drawings the numeral 1 is used to designate a body portion having side portions 2 arranged to be folded thereon. Wing portions 3 are provided upon the outer edges of the side portions 2, said wing portions being arranged to be folded upon the side portions 2 and being adapted to fold with the side portion upon the body portion 1.

Slots 4 are formed adjacent the ends of the body portion 1 to receive the ends of a

fashion card 6 for detachably mounting said card upon the folder.

A plurality of sample pieces 7 of material, such as fabric and the like, are secured upon the edges of the card 1, said samples being arranged to extend across the adjacent side portions 2 to be enclosed between said side portions and their respective wing portions 3 when said wing portions are folded thereonto.

A plurality of apertures 8 are formed in the wing portions 3, said apertures being shaped to represent suitable articles of merchandise. The apertures 8 are arranged to match with the samples 7 in such manner that when the wing portions are folded upon the side portions the samples will be observable through the apertures so as to simulate the appearance of the article represented by the aperture if fashioned from the material of the sample.

The device is designed primarily for the display of styles and materials for wearing apparel, the device being illustrated in connection with the display of styles and materials for head gear. In practice the card 6 is printed with pictures illustrating current fashions in a particular article of apparel, and samples of fabrics of various colorings and characters of weave of the prevailing styles are secured upon the edges of the card.

The card is then mounted upon the body portion of the folder by inserting the ends of the card through the slots 4, the samples being extended across the side portions 2 of the folder and the wings 3 folded down thereover. In this manner the sample is covered except for these portions observable through the apertures 8 of the wings, which as above mentioned will present the appearance of the article as it appears when fashioned from the material of the sample. It will be noted that the wing is not secured upon its free end, and that the outer ends of the samples are likewise not secured. This permits the wing to be folded away from the side portion and the samples rendered accessible for inspection as to character and quality.

From the above description it will be apparent that I have provided an improved device wherein the prevailing styles in designs and materials are attractively and conveniently presented, and which in addition presents a similitude of the article as it actually appears when fashioned from a

particular fabric. Thus in the sample, I have illustrated the card 6 as bearing pictures of the prevailing styles in men's caps, to which card are attached samples of fabrics of popular style for making caps and hats. The wings have apertures cut therein to represent conventional types of head gear which, when the wing is folded onto the side portion 2 and samples 7 affords a similitude of an article fashioned from the particular fabric adjacent each aperture.

The device is of particular value in wholesale trades in soliciting trade from out of town customers. The device is folded as shown in Fig. 3 of the drawings, the wings and side portions being folded inwardly successively into compact form suitable for mailing, to regular or prospective customers to give a complete and comprehensive display of the prevailing fashions, from which the customer may intelligently select his stock. The cards 6 are made detachable for the particular purpose of permitting additional cards and sets of samples to be forwarded to the customer to replace or supplement former cards 6 as the styles and fashions change throughout the several seasons, in this manner the expense of preparing and mailing the entire folder with each change in fashion is largely eliminated as the new fashion cards and samples may be used by the customer in connection with a previously furnished folder. The advantages of the device as a means of securing and retaining trade is obvious and needs no particular description.

While I have illustrated the device in connection with men's hats and caps it is of course obvious that the folder may be adapted for use in connection with other articles of wearing apparel in a similar manner without departing from the spirit of my invention. In like manner the size of the device and the number of styles and samples displayed may be altered to suit the requirements of any particular trade. I therefore do not restrict myself to the precise disclosure made but wish to avail myself of all substitutions and modifications that may fall within the scope of the appended claims.

Having thus described my invention what I claim as new and desire to secure by Letters Patent is:

55 1. A sample folder comprising a body portion; a side portion foldable upon the body portion; a wing foldable upon said side portion, said wing portion having a plurality of apertures shaped therein to represent an article of merchandise; a fashion card adapted for detachable mounting upon the body portion of the folder; a plurality

of samples of material secured upon said card and arranged to normally lie between the side portion and the wing, said samples being observable through the apertures in said wing to simulate the appearance of an article fashioned from the material of the sample.

2. A sample folder comprising a body portion having slots formed adjacent the ends thereof; a side portion foldable upon said body portion; a wing foldable upon the side portion said wing portion having apertures shaped therein to represent an article of merchandise, a fashion card, the ends of which card are adapted to be engaged by the slots of the body portion for detachably securing said card thereto; a plurality of samples secured upon the sample card and arranged to extend between the side portion and the wing when said wing is in folded position, said samples being observable through the apertures in the wing to simulate the appearance of an article fashioned from the material of the sample.

3. A sample folder comprising a body portion; side portions formed upon each side of the body portion and foldable upon said side portions and foldable therewith upon the body portion, said wing portions having apertures shaped therein to represent an article of merchandise; a fashion card; means for detachably mounting said card upon the body portion; a plurality of samples of material secured upon the edges of the card and arranged to normally extend over the side portions, said samples being observable through the apertures in the wings to simulate the appearance of an article fashioned from the material of the sample.

4. A sample folder comprising a body portion having slots formed adjacent the ends thereof; side portions foldable upon the body portion; wings foldable upon the side portions and also foldable therewith upon the body portion, said wings having apertures shaped therein to represent an article of merchandise, a fashion card having the ends thereof arranged to engage the slots in the body portion for detachably mounting the card thereon; and a plurality of samples of material secured upon the sides of the card and arranged to extend over the side portions to be covered by the wing portions when folded thereon, said samples being observable through the apertures in the wings to simulate the appearance of an article fashioned from the material of the sample.

In witness whereof I hereunto set my signature.

CHARLES H. GOLDMAN.
